UNITED STATES PATENT OFFICE.

FRANCIS M. STAMBAUGH, OF ST. LOUIS, MISSOURI, ASSIGNOR TO THE AMERICAN BRAKE COMPANY, OF ST. LOUIS, MISSOURI, A CORPORATION OF MISSOURI.

GEARING.

No. 811,751.

Specification of Letters Patent.

Patented Feb. 6, 1906.

Application filed March 7, 1905. Serial No. 248,849.

To all whom it may concern:

Be it known that I, FRANCIS M. STAMBAUGH, a citizen of the United States, residing at St. Louis, Missouri, have invented a certain new and useful Improvement in Gearing, of which the following is a full, clear, and exact description, such as will enable others skilled in the art to which it appertains to make and use the same, reference being had to the accompanying drawings, forming part of this specification, in which—

Figure 1 is a side elevational view of my improved machine. Fig. 2 is a sectional view on line 2 2 of Fig. 1. Fig. 3 is a sectional view on line 3 3 of Fig. 2, and Fig. 4 is a top plan view of the parts shown in Fig. 3.

This invention relates to a new and useful improvement in a machine for assembling part of a slack - adjuster, particularly the clevis on the threaded rod, the object being to firmly screw the clevis onto the rod while the rod is held in a vise and by so forcibly driving the clevis home avoid the use of cross pins or keys for permanently connecting the clevis to the rod. Heretofore these parts have been assembled by hand; but it is obvious that the application of manual power to force the clevis home is not only tiresome, but the length of the wrench-bar necessary to apply the required power to the clevis renders such manual assemblage awkward.

My present invention consists in the construction, arrangement, and combination of the several parts, all as will hereinafter be described, and afterward pointed out in the claim.

In the drawings, 1 indicates a frame carrying a stationary vise-jaw 2, preferably faced with Babbitt metal, so as to avoid mutilation of the threads of the rod 3, which is clamped thereon and upon the end of which a clevis 4 is to be secured.

5 indicates a movable vise-jaw, also faced with Babbitt metal where it engages the rod 3, said movable jaw being carried by a cross-head 6, connected to rods 7, passing down through suitable guides on the frame 1. The lower ends of these rods 7 are pivotally connected to links 8, forming members of a compound toggle, said links 8 being pivotally connected at the connecting-points of levers 9, having fixed fulcrums on parts of the frame

1, while levers 10 are connected to a piston-rod 11. Rod 11 has a head at its upper end operating in a cylinder 12, under which is arranged a spring 13. A pipe 14, leading from some suitable source of compressed-air supply, is provided with a three-way valve 15, whereby pressure is admitted to and exhausted from the cylinder above the head of the piston.

16 indicates a pulley having a friction-face, with which coöperates a friction-clutch 17. Pulley 16 is loosely mounted on shaft 18, while the clutch is keyed to said shaft and longitudinally movable with respect thereto.

19 indicates a spring - follower slidingly mounted on shaft 18 and bearing against a spring 20, whereby yielding pressure may be exerted against the friction-clutch 17. A foot-treadle 21 is designed to be operated by the operator in yieldingly pressing the clutch 17 against the friction-face of the pulley. Shaft 18 is provided with a pinion 22, meshing with a gear 23, whose shaft is provided with a tongued mandrel 24.

The operation is as follows: The clevis is first introduced onto the tongue of the mandrel, which normally is at rest. The threaded bar 3 is now placed between the vise-jaws 8 and adjusted in the proper position. The tapped opening in the clevis for receiving the bar 3 is preferably tapered slightly, so that the clevis can be firmly driven home. When the bar 3 is in position, valve 15 is operated to admit pressure on top of the piston, which transmits motion through the compound toggle leverage to the movable vise-jaw, firmly clamping the rod 3 in position, the power applied to the vise-jaw and the extended area of said jaws preventing the rod 3 from being rotated during the time that the clevis is being secured in position thereon. The operator now depresses the treadle 21, with a result that the mandrel 24 is rotated in the proper direction to screw the clevis onto the rod 3, the operator of course properly adjusting the clevis so that its tapped opening will receive the threaded end of rod 3. The clevis will be screwed home until the tapered opening prevents further movement except by the application of greater power, and herein lies the value of the yielding pressure on the friction - clutch. The operator usually de-

presses the treadle 21 by foot, and the greater the weight applied to the treadle the greater will be the frictional contact between the clutch - faces, and consequently the greater amount of power applied. In practice the operator practically puts most of his weight on the treadle, a heavy person of course causing the clevis to be more firmly seated home. When the clevis is seated home, it comes to a position of rest, indicating that it has been screwed in position as far upon the rod 3 as the power applied to the treadle 21 warrants, and thereupon the operator releases the treadle and exhausts the air from on top of the cylinder, the spring 13 raising the rod 11 and the movable vise-jaw enabling the operator to remove the rod 3 and its attached clevis from the machine.

I am aware that minor changes in the construction, arrangement, and combination of the several parts of my device can be made and substituted for those herein shown and described without in the least departing from the nature and principle of my invention.

Having thus described my invention, what

I claim as new, and desire to secure by Letters Patent, is—

In a machine of the class described, a mandrel, a shaft on which said mandrel is mounted, a gear on said shaft, a drive-shaft, a pinion thereon that meshes with said gear, a loose pulley mounted on said drive-shaft and provided with a friction-face, a clutch member splined to said shaft and having a coöperating friction-face, a follower reciprocatingly mounted on the drive-shaft, a spring surrounding the drive-shaft and interposed between the follower and the clutch member, and a lever in engagement with said follower and adapted to be actuated for moving the clutch member into engagement with the loose pulley and holding it there with a yielding pressure; substantially as described.

In testimony whereof I hereunto affix my signature, in the presence of two witnesses, this 3d day of March, 1905.

FRANCIS M. STAMBAUGH.
